UNITED STATES PATENT OFFICE.

WILLIAM DALTON, OF GLENVILLE, NEW YORK, ASSIGNOR TO GENERAL ELECTRIC COMPANY, A CORPORATION OF NEW YORK.

BLOCK FLOORING.

Application filed April 21, 1926. Serial No. 103,625.

The present invention relates to block flooring, such as is used in factories and industrial buildings, and more particularly to the construction of ducts for pipes, conduits, 5 wiring and the like in such flooring as required in connection with individual apparatus and machines located thereon.

Block flooring is usually laid over a concrete sub-floor, although it may be laid over 10 any suitable smooth foundation flooring. Its use effects a material saving in floor cost over other forms of flooring, such as wooden planks for example, and when composed of wooden blocks has been found to be more 15 durable than the plank flooring.

The advantages of decreased cost and durability have heretofore been accompanied by the disadvantage that the placing of ducts in block flooring has necessitated 20 cutting and fitting the blocks about the ducts which were fixed in place before the blocks were laid. The cutting and fitting of the blocks results in a very poor and loose floor construction and interferes with the 25 speed of laying of the blocks, thereby increasing the labor cost.

It is the object of this invention to provide an improved duct for block flooring which is adjustable in length, width and 30 alignment whereby it accommodates variations in the floor blocks without the usual cutting and fitting, and the method of providing such ducts in a block floor without interfering with the rapid laying of the 35 blocks.

For a further consideration of what is believed to be novel and the invention, attention is now directed to the accompanying drawing, the description thereof and the 40 appended claims.

In the drawing, Fig. 1 is a plan view, partly in section, of a portion of the floor and one side wall of a modern factory building provided with floor ducts in accordance 45 with the invention; Fig. 2 is a sectional view on an enlarged scale of a floor duct of Fig. 1, and Fig. 3 is a view in perspective, also on an enlarged scale, but reduced from that of Fig. 2, of a floor duct in the course of being completed, together with a distribution duct connected therewith.

Referring to the drawing, 5 is a longitudinal or side wall of a factory building and

6 is a sub-floor adapted to receive a block covering 7. In the present example the sub-floor is, together with wall 5, of concrete construction and the block covering 7 comprises duplicate wooden blocks 8 laid in staggered rows 9 with the grain extending vertically, which is the usual arrangement 55 of blocks in a block floor, although the invention is not limited to any particular form of block covering. The rows of blocks extend transversely of the building and are laid in successive rows, from one end of the building to the other longitudinally thereof, each row being rammed under pressure against the preceding row so that the finished floor is tight and smooth with no 60 loose blocks.

The floor is laid out with a longitudinal main central aisle 10 and branch machine bays 11 located between floor supporting columns 12 and connected with the main aisle.

In each bay are one or more branch ducts 75 13 extending transversely out from a distribution duct 14 toward the main aisle 10. In the present example two branch ducts are provided in each aisle, while the distribution duct 14 is adjacent wall 5, although the invention is not limited to any 80 number of ducts or their location on the floor except as hereinafter pointed out. This duct arrangement is duplicated on the opposite side of aisle 10, as indicated by branch ducts 15 corresponding to branch ducts 13, the remainder thereof not being shown for the reason that this arrangement is a duplication 85 of that shown, as above mentioned.

The ducts are formed by a pair of spaced, 90 parallel stringers 16 laid on the sub-floor 6 and a sectional cover plate 17 laid over the stringers. The thickness of the stringers is such that the cover plates lie flush with the surface of the blocks 8, as indicated in Fig. 2. The stringers and cover plates may be of any suitable material, such as for example long leaf yellow pine and corrugated sheet iron or steel respectively. The plates are of a thickness sufficient to provide the proper 95 supporting strength for all objects which may be placed upon them or moved over them in the regular use of the building, such as small loaded electric trucks. In this connection it will be noted that the ducts are 100 so placed that they do not lie in the path of

the usual traffic about the floor, since they do not extend into or across the main aisle 10 and are located adjacent opposite sides of the branch machine bays 11 and on opposite sides of the central aisle therein which is open.

The location of machines which are supplied with conduit and wiring connections from the ducts are indicated by dotted squares 18. To provide connection with a duct, a cover plate section is removed adjacent the machine, drilled to provide openings for the connecting conduits, wiring and the like and replaced after the connection is made. The use of a sectional covering means for the ducts permits convenient access thereto at different points without removing the entire covering. In the present example the thickness of stringers 16 is made such that the covering means lies flush with the block floor level, but in any case it is desirable that the duct forming means should be flush with the floor level.

With the above-described arrangement of ducts, the distribution ducts are adjacent the walls and receive connection with conduits, such as a main conduit 20 directly from a duct 21 in wall 5. In the present example 20 is a wiring conduit containing distribution cables 22 which are laid in duct 14 and connected with feeder cables 23 laid in ducts 13.

The distribution ducts are not necessarily located adjacent the walls of the building, as shown, although this location is at present preferred in factory buildings for the reason that easy connection is made thereto from wall conduits, such as conduit 20, and for the reason that they are then not in the line of traffic while being easily accessible at all times.

The main consideration in placing the distribution ducts is that they extend longitudinally of the floor, that is, so that the rows of floor blocks run transversely with respect to them. This is for the reason that in providing a floor in accordance with the invention the distribution ducts are laid down on the sub-floor before the laying of the blocks is commenced and thus serve as longitudinal boundaries or guides for the blocks much in the same manner as do the side walls of the building when such floors are laid without ducts. Thus the provision of such distribution ducts does not interfere with the usual rapid laying of the blocks but serve to guide the laying of the blocks in the same manner as the usual side walls or other boundaries of floor areas.

If time permits before the blocks are laid, the stringers forming the sides of the distribution ducts may be permanently secured to the floor by any suitable means in the desired spaced relation to form a duct of the proper width or, in case time does not per-

mit them to be secured to the sub-floor before the block flooring is laid, the stringers are laid in the desired positions and held in the desired spaced relation to each other by any suitable means, such as floor blocks 25, 70 dropped in between them at intervals, as indicated in Fig. 3.

The block flooring is then laid along and abutting the distribution duct or ducts, each row being rammed under pressure against the preceding row until a desired location for a branch duct 13, or a line of branch ducts as represented by ducts 13 and 15 in end to end relation, is reached. A pair of stringers are then laid on the sub-floor for each duct desired, abutting at one end a stringer 16 forming the inner wall of the distribution duct 15, as indicated in Fig. 3, and extending from said stringer along the edge of the block flooring, indicated at 26. 85 The stringers for the branch ducts 13 are blocked apart to form the duct of the desired width, by any suitable means, such as floor blocks 27 placed at intervals along the duct between the stringers. 90

The overall width of the duct and stringers is made equal to that of a certain number of rows of floor blocks, for example three as indicated in Fig. 1, so that the rows of blocks are unbroken across the width of the floor. In the present example the ducts and stringers are each substantially equal in width to a floor block, that is, a row of blocks, whereby the floor blocks may be used to space the stringers to provide the total overall width of these rows without chipping the spacing blocks except to meet slight variations in the width of the blocks forming the preceding rows. 95

When the stringers forming the branch duct or ducts have been extended from the distribution duct the desired distance, for example out to the main aisle 10, by providing stringers of the correct length or additional stringers in continuation one of the other as indicated at 28, Fig. 1, and blocked or otherwise temporarily held apart in spaced relation to each other as above explained, the laying of the succeeding rows of block flooring indicated at 29 and 30, 110 Fig. 3, continues as before until a new location for a second line of branch ducts is reached when two stringers with suitable temporary spacing means between them are put down in place of a certain number of 115 rows of blocks for the length of branch duct desired. The laying of the rows of blocks then continues as before until in this manner the entire floor covering with ducts in place is laid. 120

By this arrangement the work of laying the block flooring is uninterrupted since the stringers and spacers replace in part, certain rows of blocks and are laid as rapidly as the blocks which they replace. It further 125

permits the block rows to be rammed to a tight fit and the duct stringers to thereby fit tightly between adjacent rows of blocks without chipping or fitting said adjacent 5 rows since the stringers and spacing means for the ducts are movable with the adjacent rows of blocks during the ramming process. The entire floor is thus laid tightly and permanently without interruption and without 10 the usual chipping fitting required adjacent each duct as heretofore, resulting in a less expensive and better floor.

Following the laying of the block flooring, the stringers, including those for the 15 distribution ducts if the latter have not been initially fastened, are fastened to the sub-floor, the block spacers removed, and junctions between the distribution and branch ducts made by cutting through the stringers of the distribution ducts in continuation 20 of the branch ducts, as indicated at 31, Figs. 1 and 3.

In the preferred arrangement shown in the present example, for use over concrete 25 sub-floors, the stringers are provided in advance with spaced, counterbored bolt holes 32 to receive expansion bolts 33 which are secured in drilled holes in the sub-floor, the latter holes being drilled with the bolt holes 30 as guides. In Fig. 3, the stringers are shown bolted down and cut through to form the junction between the branch and distribution ducts preparatory to removing the spacing blocks 25 and 27. In certain cases 35 the blocks are removed as soon as the stringers are fastened to the sub-floor. In any event it will be seen that the stringers when fastened, serve to hold the block rows in 40 compressed relation to each other in addition to forming the side walls of the ducts.

As a final operation, the cover plates are laid over the ducts, except where wiring or conduit work is to be installed immediately, to keep the ducts clean during the installation 45 of machinery and apparatus. The cover plates of the present example are fastened to the stringers by flat head wood screws indicated at 34, Fig. 1, so that the finished and covered duct presents the same 50 smooth surface as the block covering on each side of it.

From the foregoing description it will be seen that a floor constructed and provided 55 with ducts in accordance with the invention may be as tightly, easily and as perfectly laid as a block floor without ducts, and does not involve additional labor and waste material costs incidental to the usual cutting and fitting of the blocks about fixed ducts as heretofore necessary. Furthermore, with the present method of construction the blocks and ducts are free to move and pack 60 tightly together when being laid, thus forming a more permanent floor which is finally secured to the sub-floor at points along the

ducts for the purpose of removing the temporary spacing means and holding the block rows in compressed relation as laid. In other words, the means forming the duct side walls are secured to the sub-floor only 70 after the whole is laid and each unit thereof has assumed a final position of equilibrium in response to the ramming pressure to which the rows are subjected during the laying process. Thus the ducts of the present invention do not prevent the floor blocks from moving and equalizing undesirable pressures, thereby preventing loose fitting blocks at one point and lifted, tightly pressed blocks at another point in the finished floor.

It will be appreciated that the branch ducts may be of any length and may, if desired, extend continuously across the floor 75 for example, in which case the duct and stringer width is not important and need not equal that of a certain number of rows 80 of blocks, since the duct and stringers extend fully across the floor and occupy full rows in length.

In the usual case such as that of the present example, the branch or transverse ducts and stringers occupy the space in one or more transverse rows which ordinarily 90 would be taken by blocks, but do not extend the full length of the rows to provide aisle 95 10 and hence must conform in width to the blocks in a multiple of one dimension thereof, depending upon the number of rows of blocks within which the duct and stringers lie, the shape of the blocks and the manner in which they are laid. That is, had the 100 floor blocks in the floor shown in the drawing been laid side by side instead of end to end, the rows of blocks would have been wider and the means providing the ducts 13 and 15 would have an overall width of some 105 multiple of the width of the rows of blocks as before, which in this assumed case would be the length of a block and not its width.

It will therefore be seen from the foregoing that the width of the means forming a duct other than a longitudinally extending distribution duct like duct 14, must be of some multiple of one dimension of a block 110 if duplicate floor blocks are to be used but that the lengths of all ducts are fixed only by the dimension of the floor in the direction in which the ducts extend. Special blocking required to fit about a duct would involve greater cost with no greater utility or durability. Hence floors provided by duplicate block flooring is the type of flooring 115 to which the duct arrangement of the present invention is best adapted, although it will be appreciated that it is not limited thereto and may be applied to any block flooring having blocks of such shape that substantially parallel stringers may be thrown down and temporarily spaced to fit 120 125 130

into the block arrangement without chipping or fitting and without interrupting the general progress in laying the floor.

The distribution and branch duct arrangement of the present example, together with the main and branch aisle layout of a floor substantially as shown in the present example, is particularly well adapted to factories and industrial buildings, both from 10 a cost and an operation view point, and represents the present preferred embodiment of the invention, although the latter is not limited to such an arrangement as has hereinbefore been pointed out.

15 What I claim as new and desire to secure by Letters Patent of the United States, is:

1. The combination with a sub-floor, of a block covering therefor, and means forming a duct in the covering, said duct being open 20 at the top, one dimension of which means is equal to a multiple of the transverse dimension of a block in said covering.

2. The combination with a sub-floor, of a covering therefor comprising a layer of 25 blocks and means forming a duct in said covering, a cover for the duct supported by said means, the overall thickness of the cover and duct forming means being equal to the thickness of the floor covering and the over-all width of the duct-forming means being 30 equal to a multiple of one dimension of a block in said covering.

3. The combination with a sub-floor, of a block covering therefor, and means forming 35 a duct in the covering, said means comprising spaced stringers, the overall width of the stringers and space between them being substantially equal to a multiple of one dimension of a block forming said covering.

40 4. The combination with a sub-floor, of a covering therefor comprising a layer of blocks laid thereon in parallel tightly compressed rows and means forming a duct in the covering between certain of the block 45 rows, said means comprising spaced stringers laid on the floor and secured there-to to hold the block rows in compressed re-

lation to each other, and a cover plate which lies flush with the surface of the block covering.

50 5. The combination with a sub-floor, of a covering therefor comprising a layer of blocks laid thereon in parallel tightly compressed rows, and means forming ducts in said covering between certain of said rows, 55 said means comprising spaced stringers compressed between said rows of blocks and secured to the sub-floor whereby said stringers form the side walls of the ducts and hold the block rows in said compressed relation 60 to each other.

6. In a floor covering, the combination with a layer of blocks providing a floor surface, of means forming a duct within the block layer, said means having an overall 65 width substantially equal to a multiple of one dimension of a block and a cover for the duct supported by said means substantially flush with the floor surface.

7. In a floor covering, the combination 70 with a layer of blocks providing a floor surface, of means substantially flush with said surface forming a duct within the block layer, said means having an overall width substantially equal to a multiple of one dimension of a block, said means comprising 75 a pair of spaced stringers and a covering member therefor.

8. The combination with a sub-floor, of a block covering therefor, said covering comprising parallel rows of duplicate blocks, a pair of spaced stringers between certain of said rows of blocks forming the side members of a duct, means forming a cover for said stringers and duct, said stringers and 80 cover means being substantially equal in thickness to the floor blocks and said stringers and duct being substantially equal in overall width to a multiple of the width of one of said rows of blocks.

90 In witness whereof, I have hereunto set my hand this 19th day of April, 1926.

WILLIAM DALTON.

CERTIFICATE OF CORRECTION.

Patent No. 1,632,590.

Granted June 14, 1927, to

WILLIAM DALTON.

It is hereby certified that error appears in the printed specification of the above numbered patent requiring correction as follows: Page 4, line 20, claim 1, strike out the word "one" and insert instead the words "the transverse", and line 21, strike out the words "the transverse" and insert instead the word "one"; and that the said Letters Patent should be read with these corrections therein that the same may conform to the record of the case in the Patent Office.

Signed and sealed this 12th day of July, A. D. 1927.

Seal.
